(57) **CLAIM**

The ornamental design for a wireless charging stand for electronic device as shown and described.

DESCRIPTION

FIG. 1 is a front, top, and left side perspective view of a wireless charging stand for electronic device, showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a rear, top, and left side perspective view thereof.
